US00D715800S

(12) **United States Design Patent**
Cornelison

(10) **Patent No.:** **US D715,800 S**
(45) **Date of Patent:** **** Oct. 21, 2014**

(54) **WALL-MOUNT FINGERPRINT SCANNER**

(71) Applicant: **Access Biometrics LLC**, Orlando, FL (US)

(72) Inventor: **Michael Cornelison**, Altamonte Springs, FL (US)

(**) Term: **14 Years**

(21) Appl. No.: **29/482,624**

(22) Filed: **Feb. 20, 2014**

(51) **LOC (10) Cl.** **14-02**

(52) **U.S. Cl.**

USPC **D14/384**
